Eugene A. Robe, INVENTOR.

BY
Geo. P. Kimmel.
ATTORNEY.

UNITED STATES PATENT OFFICE.

EUGENE A. ROBE, OF NEW CONCORD, OHIO.

RECEPTACLE.

Application filed April 4, 1922. Serial No. 549,557.

To all whom it may concern:

Be it known that I, EUGENE A. ROBE, a citizen of the United States, residing at New Concord, in the county of Muskingum and State of Ohio, have invented certain new and useful Improvements in Receptacles, of which the following is a specification.

This invention appertains to certain improvements in shipping or storage receptacles generally, and more particularly to a type of the same adapted to maintain the contents thereof at an even temperature, either hot or cold, throughout the desired period of shipment or storage.

The principal object of the invention is to provide for a receptacle or container of the class set forth, and one of a novel, efficient and substantial construction and arrangement, but which will be comparatively light in weight and inexpensive to manufacture.

Another object of the invention is to provide for a receptacle or container as hereinbefore characterized, and one of a double wall construction, whereby to have a vacuum created within the space between the walls thereof, and wherein a means is provided to strengthen these walls to withstand the ordinary hard usage to which the receptacle or container may be subjected, and without injury thereto.

With the foregoing and other objects in view, the invention resides in the certain new and useful construction and arrangement, which will be hereinafter more fully described, set forth in the appended claims, and illustrated in the accompanying drawing, in which:—

Figure 1 is a vertical section through a preferred embodiment of the receptacle or container,

Fig. 2 is a bottom plan view of the lower end of the intermediate reinforcing shell of the device, and showing one form of valved closure for the vacuum space of the container or receptacle, and,

Fig. 3 is a similar view, but showing a modified form of closure for the vacuum space of the container or receptacle.

Referring to the drawings, 10 indicates an outer casing open at its top and having a closed bottom 11. The body of the casing 10, at a point removed from its open end, is formed with an outwardly extending bead 12 which provides a seat for the edge of the flange of a cover 13, which is employed for closing the open end of the casing 10. The

cover 13, as well as the casing 10, is provided with a lining 14, such as sheet asbestos or other suitable material.

Fitted within the casing 10 is an intermediate shell 15 having on its outer surface a spiral flange or web 16 spacing the same in position with respect to the inner lined wall of the casing. The lower open end of this shell 15 is inwardly thickened to provide an inwardly tapered annulus 17, which has its tapered face threaded to receive therein a closure 18. This closure 18 is preferably of a concavo-convex formation and is formed to provide a nippled opening 19, which has its bore threaded to receive therein a screw valve plug 20. To reinforce the concavo-convex wall of the closure 18, in the form of the same as shown in Fig. 2, the same is provided with a series of strengthening ribs 21 radiating from the valve nipple 19, or, in the form of the closure as shown in Fig. 3, the reinforcing ribs 21' extend across the concavity thereof in parallel relation one with respect to the other, the inner of said ribs 21 being spaced to either side of the valve nipple 19. The upper open end of this shell 15 is inwardly curved as at 22, and this curved portion is inturned to provide an annular flange 23, which is threaded to receive therein the threaded open end of an inner container or receptacle 24, and, when the latter is properly positioned, it will be securely supported with its walls spaced from the walls of the shell 15, and with the edge of its upper open end flush in the plane of the upper open end of the shell. The open end of the container or receptacle 24 is closed by an inwardly depressed friction cover 25 having an outturned flange 26 snugly contacting the outer wall of the curved portion 22 of the shell body, when properly positioned. To support and strengthen the center of the cover 13, of the outer casing 10, the inwardly depressed wall of the container cover 25 is formed to provide a centrally and outwardly disposed conical depression or projection 27, which has its apex terminating in the plane of the upper surface of the flanged portion 26, whereby the inner lined surface of the closure 13 will bear directly thereon, when placed in position on the outer casing 10, so that a dead air space is formed in the depression of the cover 25 at the outer end of the container 24.

In assembling the device as thus constructed and arranged the container 24 will

be secured in position within the shell 15, and the end closure 18 at the lower end of the latter, when a vacuum will be drawn in the space between the opposed walls of the 5 container and the shell, the drawing of the vacuum being affected through the plug valve 20 in the closure 18. The assembled container and shell will now be inserted into the casing 10, when the channelway of the 10 spiral flange or web 16 will be packed with asbestos, mineral wool or the like 28, the same filling the space between the shell 15 and the interior of the casing 10 flush with the upper open end of the latter, whereby to 15 be tightly packed when the casing cover 13 is placed in position. The interior of the container 24 is preferably lined with waxed paper or the like 29, so that the material to be placed within the same will not come in 20 contact with the bare wall or walls thereof.

This shipping and storage container has been designed to greatly reduce the weight and manufacturing cost of such devices, and the reinforcing means; i. e., the spiral flange 25 16 of the shell 15, the ribs 21, 21', of the bottom closure 18 of the latter, and the conical projection 27 of the upper closure 25 thereof; is deemed ample to afford sufficient resistance and strength to the walls of the outer casing 10 to withstand any and all pressures brought to bear on the same during the ordinary hard usage accorded articles during shipment and without injury thereto.

In its preferred embodiment, the receptacle or container in its entirety will be made in cylindrical form, substantially as shown, and preferably of aluminum, although any other suitable metal may be employed for the purpose, the intermediate 35 shell 15 being of cast metal and the inner container 24 and the outer casing 10 of sheet metal. The receptacle may be conveniently and economically used for the shipment or storage of any and all classes of perishable 40 food stuffs, either solid or liquid, such as fish, meat, milk, oysters, ice cream and other frozen delicacies, or the like.

It will be understood that, while a preferred embodiment of the device has been described 50 and illustrated herein in specific terms and details of construction and arrangement, various changes in and modifications of the same, such, for instance, as replacing the metal container closure, indicated by the portions 55 25, 26 and 27 (but not necessarily including 27 in shape), with one made from cork or the like, may be resorted to without departing from the spirit of the invention, or the scope of the claims appended hereto.

60 Having thus fully described the invention, what is claimed, is:—

1. In a receptacle as characterized, an outer cylindrical casing, an inner cylindrical container, a cylindrical member interposed 65 between the casing and container and ar-

ranged to provide spaces between its outer wall and the inner wall of said casing and its inner wall and the outer wall of said container, said member having an inner and outer open end, said container engaging with 70 the outer end of said member for closing it, a removable closure for an inner end of said member, a spiral element interposed between the inner wall of said casing and the outer wall of said member to strengthen 75 said walls against injury or collapse, a packing filling the outer space between said casing and said member and within the channelway formed by said spiral element, and means whereby a vacuum may be drawn in 80 the space between the inner wall of said member and the outer wall of said container.

2. In a receptacle as characterized, an outer cylindrical casing, a cylindrical shell disposed within said casing, and having its 85 outer end in-turned and merging into an inwardly extending threaded annular flange, said shell having its inner end formed with a threaded tapered annular flange, a spiral flange formed on the outer wall of said shell 90 and spacing the same inwardly of the inner wall of said casing, a container carried within said shell and spaced from the wall thereof, and further having threaded engagement with the flange at the outer end 95 of the shell for closing the outer end of the latter, a removable closure engaging said tapered flange, a packing filling the channel space of said spiral flange between the casing and shell, means for drawing a vacuum 100 within the space between said shell and said container, a cover closing said container, and a cover closing said outer casing and forming a dead air space between the same and the cover of said container.

3. In a receptacle as characterized, an outer cylindrical casing, a normally open ended cylindrical shell disposed within said casing, and having its outer end formed with an inwardly extending threaded annular flange and its inner end with an inwardly tapered threaded annular flange, a spiral flange formed on said shell and spacing the same from said casing, a container suspended within said shell and engaging with the flange at the outer end of the shell for closing said end and further spaced from the walls of the shell; a closure engaging said tapered flange at the inner end of said shell, means carried by said closure whereby a vacuum may be drawn in the space between said shell and said container, a packing filling the space between said casing and said shell and the channelway formed therein by said spiral flange, a closure for said container, and a closure for said casing and forming a dead air space between the same and the cover of said container.

4. A receptacle for the purpose set forth 130 comprising an outer casing, a shell arranged

therein and having its outer end provided with an inwardly extending flange and its inner end opened, a removable closure mounted in the inner end of said shell, a 5 container suspended within said shell and engaging said flange and further closing the outer end of the shell, a flanged closure mounted in the outer end of the container and engaging the outer edge of the container 10 and shell, and a closure mounted on the outer end of said casing, a liner arranged against the inner face of said casing throughout and abutting against the inner end of the shell and the closure at said 15 inner end of the shell, and a liner positioned against the inner face of the closure for the casing and abutting against the flange of the closure for the container.

5. A receptacle for the purpose set forth

comprising an outer casing, a shell mounted 20 therein and spaced therefrom and having open ends, a container suspended within and spaced from said shell and further closing the outer end of the shell, a concavo-convex closure mounted in the inner end of the 25 shell, means carried by said closure whereby a vacuum may be drawn in the space between said shell and container, and a closure mounted on said casing, a lining for said casing and its closure, a spiral spacing means 30 carried by the shell and extended to said lining, and a packing interposed between the lining of the casing and the shell and between the spacing means.

In testimony whereof, I affix my signature hereto. 35

EUGENE A. ROBE.
